UNITED STATES PATENT OFFICE.

JOHN F. GODFREY, OF ELKHART, INDIANA.

SELF-DUMPING BUCKET.

1,258,890.

Specification of Letters Patent. Patented Mar. 12, 1918.

Application filed February 23, 1917, Serial No. 150,299. Renewed November 1, 1917. Serial No. 199,800.

To all whom it may concern:

Be it known that I, JOHN F. GODFREY, a citizen of the United States, residing at Elkhart, in the county of Elkhart and State of Indiana, have invented new and useful Improvements in Self-Dumping Buckets, of which the following is a specification.

My invention relates to self dumping buckets and more especially to buckets used for hoisting and dumping ore, coal and the like.

One object of my invention is the production of a self dumping bucket provided with wheels to enable it to be elevated on an inclined guideway or track for subsequent horizontal movement by any suitable means and finally lowered and self dumped at a point substantially remote from the top of the inclined guideway. Another object is the production of a self dumping bucket having a hinged dumping bottom provided with improved latch mechanism for locking the bottom in a closed position. Other objects will be mentioned herein from time to time and fully described.

The preferred embodiment of my invention is well illustrated in the accompanying drawings in which Figure 1 is an end elevation of a bucket embodying my invention; Fig. 2 is a side elevation of the bucket; Fig. 3 is a top plan view; Fig. 4 is a bottom plan view; and Fig. 5 is a fragment showing the carrier and latch mechanism for the dumping bottom.

Similar numerals of reference refer to similar members and parts of members throughout the several views on the drawings.

Referring to the drawings in detail, the numeral 1 indicates a bucket body formed of any suitable material and open at its top for loading, provided with a hinged dumping bottom, as will be hereinafter described, for discharging the bucket load. A bail 2 is attached to the bucket 1 to which a hoisting cable may be connected in any suitable manner, said bail being pivotally carried upon the wheel axles 3, 3 which are rigidly mounted upon the bucket body and upon which the carrying wheels 4, 4 are revolvably mounted. The numerals 5, 5 indicate wheel axle brackets, or end bearing members, rigidly fastened to the bucket body for supporting the outboard end of the wheel axles 3.

The numeral 6 indicates the bucket dump-

ing bottom provided with suitable hinge members mounted upon the bucket body at 7, 7, and adapted to be retracted by the springs 8, 8 after the discharge of the bucket load, said springs being attached to the bottom and bucket at 9 and 10, respectively. The bottom 6 is provided also with a channeled retainer bar 11 extending across the under side thereof and to which it is rigidly fastened in any suitable manner such as bolts or rivets, one end of which bar projects somewhat beyond the edge of the bottom 6. The numeral 12 indicates a shoulder carried by the bar 11 and adapted to serve as an abutment member, or portion, for the latch hereinafter described.

The numeral 13 indicates a latch hook pivotally mounted at 14 upon the bucket bottom carrier member 15, the latter being pivotally supported upon the pin 16 which is carried in the pin brackets 17, 17 rigidly fastened to the bucket body in any suitable manner. The numeral 18 indicates a supporting ledge provided on the member 15 and upon which the end of the retainer bar 11 rests and upon which it is normally confined by the engagement of the latch hook 13 with the retainer bar shoulder 12. The carrier 15 is provided with the extension 19 upon the lower end of which is provided a pair of laterally projecting arms 20, 20, one of said arms being suitably apertured at 21 to receive and guide the latch actuation rod 22, the latter being pivotally fastened to the latch hook 13 by a pin 23. The latch actuation rod 22 is provided with a knob 24 at its lower extremity, said knob being normally spaced somewhat from the arm 20 to permit of upward movement thereof and the rod 22 when the latch hook 13 is engaging the shoulder 12 for releasing such engagement.

The loaded bucket is emptied by lowering it until the knob 24 strikes the floor, or surface of the depository, thereby raising the latch hook 13 and unlatching the retainer bar, and thereby the bottom 6, whereby the carrier member 15 is free to be swung on its pivot 16 to disengage the ledge 18 from the end of the retainer bar 11, such disengagement being effected by the contact of the carrier arms 20, 20 with the depository floor, or its contents, assisted by the weight of the bucket load, while the bucket 1 is swinging naturally back and forth at the end of its hoisting cable.

2
After the bucket load has been discharged by opening the unlatched bottom 6, as described, the bottom is retracted by the springs 8, 8, the end of the bar 11 forcing the carrier member 15 outward in its upward swing, the ledge 18 of said carrier member thereupon engaging beneath the end of the bar 11 on the return swing of said carrier member and the shoulder 12 is engaged by the hook latch 13, whereby pivotal movement of the carrier 15 is prevented and thereby locking the ledge 18 beneath the end of the bar 11. Normally the weight of the carrier arm 19 and the arms 20, 20 serves as a counter balance to swing the carrier member 15 into a perpendicular position, thereby positioning the ledge 18 directly beneath the end of the retainer bar 11, following the upward swing of the bottom 6, for supporting said bottom when the bucket is loaded. And when said carrier 15 swings itself into a substantially perpendicular position the latch hook 13 is lifted and dropped into engagement with the shoulder 12 of the bar 11 from which engagement it is displaced only by the upward movement of the latch rod 22 when lifted by the engagement of the knob 24 with a stop member when the bucket is lowered, as described.

30 While my improved bucket is intended primarily for handling and moving coal nevertheless it may be used for handling and transferring any divided or disintegrated materials.

35 I claim:

1. The combination with a bucket provided with a hinged dumping door, of a dumping door carrier pivotally carried by the bucket, said carrier being provided with a ledge adapted to support said door and to be moved into and out of supporting relation therewith when said door carrier is swung upon its pivot; a movable latch hook carried by said door carrier and detachably locking said carrier ledge in supporting relation with said dumping door; and latch hook disengaging means actuated when the bucket descends whereby said door carrier ledge is freed for movement out of supporting relation with said dumping door.

2. The combination with a bucket provided with a hinged dumping door, of a dumping door carrier movably carried by said bucket, said carrier being provided with a ledge adapted to support said door and to be moved into and out of supporting relation therewith when said door carrier is actuated; a movable latch hook supported by said door carrier and detachably locking said carrier ledge in supporting relation with said dumping door; a latch actuation member operatively connected with said latch hook and adapted to actuate said latch hook when the bucket descends whereby said door carrier ledge is freed for move-

ment out of supporting relation with said dumping door.

3. The combination with a bucket provided with a hinged dumping door, of a dumping door carrier movably supported by said bucket, said carrier being provided with a ledge; a shouldered member carried by said dumping door and resting upon said carrier ledge, said ledge being adapted to be moved into and out of supporting relation with said shouldered member when said door carrier is actuated; a movable latch hook carried by said door carrier and detachably engaging the shoulder on said shouldered member whereby said carrier and carrier ledge are detachably locked in supporting relation with said dumping door, shouldered member; and latch hook disengaging means actuated when the bucket descends, whereby said door carrier ledge is freed for movement out of supporting relation with said dumping door shouldered member.

4. The combination with a bucket provided with a hinged dumping door, of a dumping door carrier pivotally mounted upon the bucket, said carrier being provided with a ledge adapted to support said dumping door and to be moved into and out of supporting relation therewith when said carrier is swung upon its pivot, said carrier being provided also with a laterally projecting and apertured arm; a movable latch hook supported by said door carrier and detachably locking said carrier ledge in supporting relation with said dumping door; and a latch hook actuation rod operatively connected with said latch hook, operatively arranged in said carrier arm aperture and projecting beyond the latter, whereby said latch hook is actuated by a stop member when the bucket descends, thereby enabling pivotal movement of said door carrier.

5. The combination with a bucket provided with a hinged dumping door, of a shouldered retainer bar rigidly secured to the dumping door and projecting from one side thereof; a dumping door carrier pivotally mounted upon the bucket, said carrier being provided with a ledge adapted to engage beneath the end of said retainer bar for supporting said dumping door and to be moved into and out of supporting relation therewith when said door carrier is swung upon its pivot, said carrier being provided also with an extension and an apertured lateral projection carried by the extension thereof; a latch hook pivotally mounted upon said door carrier adjacent said ledge, the hook whereof detachably engages the shouldered portion of said retainer bar, whereby said carrier ledge is detachably confined beneath said retainer bar; and a latch hook actuation rod operatively connected with said latch hook and arranged

within the aperture of said lateral projection, said rod being movable within said aperture and provided with a knob at its lower end, said knob being adapted to engage a stop member when the bucket descends for effecting longitudinal movement of said rod, thereby disengaging said latch hook from said retainer bar shoulder and enabling piv-

otal movement of said door carrier for the disengagement of said ledge and the retainer bar.

In testimony whereof I have hereunto affixed my signature this 19th day of February, 1917.

JOHN F. GODFREY.
